UNITED STATES PATENT OFFICE.

WILLIAM D. THOMPSON, OF DETROIT, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

CAR END.

Application filed November 27, 1922, Serial No. 603,687. Renewed October 1, 1925.

The invention relates to the construction of car bodies and more particularly to car ends of that type in which a plurality of paneled metallic plates are riveted or otherwise joined to each other to form an extended sheet. In the manufacture of such plates it is advantageous to have only a single panel in each of the sections as this simplifies the pressing operation. However, for certain uses greater strength is obtained by forming a plurality of panels in certain of the sections which are combined with other sections of the single panel construction. The present invention therefore consists in such a combined single and multiple panel construction as hereinafter set forth.

In the drawings:

Figure 1 is an end elevation of a car showing my improved construction;

Figure 2 is a vertical longitudinal section through the end portion of the car;

Figures 3, 4 and 5 are respectively a top plan view, bottom plan view and side elevation of the composite metallic plate forming the car end.

My improved construction is applicable to any suitable design of car frame, but as shown, A is the end sill, B the end plate and C the corner posts constituting the end frame of the car. Extending across this frame is a metallic end plate of the following construction: D, D', D² are oblong paneled plates which extend transversely from corner post to corner post and are provided at their ends with angle flanges E for extending around said posts. Each of these paneled plates is formed with a plurality, preferably two, of panels F, F' therein which are arranged in a plane parallel to the plane of the marginal and intermediate portions of the sheet and are connected thereto by obliquely extending portions G and G' at the sides and ends. The adjacent plates overlap each other and are rigidly secured preferably by riveting. Also, the dimensions are so chosen as to secure relatively great rigidity in the composite plate, there being substantially an equal amount of metal in each of the parallel planes with sufficient transversely extending metal to carry the stresses from one plane to the other.

The combined height of the plates D, D', D² is only equal to a portion of the height

of the car and the remainder of the end is composed of sections H and H'. These are 55 similar to the sections D, D', D², with the exception that there is but a single panel of greater width in each of the sections.

A composite plate formed as described of single and multiple panel sections will have 60 a greater strength and rigidity than one formed solely of single panel sections. On the other hand, by using single panel sections for the upper portion of the composite plate, the manufacturing cost is somewhat lessened and, as the lower portion is subjected to greater stresses than the upper portion, the structure is substantially as strong as where composed entirely of multiple panel sections. 70

The plate is further reinforced by a wooden lining I, preferably formed of matched boards, extending vertically and lying flush with the inner plane. Nailing strips J for the lining are arranged in the recesses formed by the panels, these being bolted or otherwise secured in position. 75

What I claim as my invention is:

1. In a car body construction, a composite metallic plate formed of a series of overlapping pressed sheet metal sections rigidly secured to each other, the adjacent sections forming a portion of said plate being formed with a single panel pressed therein and the adjacent sections forming another portion of said plate and subjected to greater stresses than the first-mentioned sections being formed with a plurality of panels. 80

2. In a car body construction, a composite metallic plate formed of a series of overlapping pressed sheet metal sections rigidly secured to each other, the adjacent sections forming the lower portion of said plate, being formed with a plurality of panels therein, and the sections forming the remainder of the plate being formed with a single panel in each. 90

3. In a car body construction, a composite metallic plate formed of a series of oblong rectangular pressed sheet metal sections overlapping and rigidly secured to each other, a portion of said sections being formed with a single panel pressed in each and a portion normally subjected to greater stresses than the first-mentioned portion having a plurality of panels pressed therein. 100

4. In a car body construction, a composite metallic plate formed of a series of oblong rectangular pressed sheet metal sections, said sections extending transversely and having their side edges overlapping and rigidly secured to each other, the sections forming the lower portion of said plate being formed with a plurality of panels pressed in each and the sections forming the upper portion of the plate being formed with a single panel pressed in each. 45
5. In a car body construction, a composite metallic plate formed of a series of overlapping sheet metal sections having their overlapping portions secured to each other, a portion of said sections being subjected to greater stresses than another portion of said sections and being formed with a plurality of panels pressed therein, the second-mentioned portion of said sections being formed with a single panel pressed therein. 50
6. A wall structure for railway cars comprising one or more metallic plates, said wall structure having a plurality of parallel panels formed therein, said panels being connected at opposite sides to the plates and arranged with varying distances between the centers of adjacent panels. 55
7. A wall structure for railway cars comprising one or more metallic plates, said wall structure having a plurality of equal depth parallel panels formed therein, said panels being connected at their longitudinal sides to the plates, the distances between the centers of adjacent panels near the floor of the car being less than elsewhere. 60
8. A wall structure for railway cars comprising one or more metallic plates, said wall structure having a plurality of equal depth parallel panels formed therein, connected at opposite sides to said plates, and terminating within the edges of the plate, with the panels being arranged varying dis- 65
- tances between the centers of adjacent panels. 70
9. A wall structure for railway cars comprising one or more metallic plates, said wall structure having a plurality of parallel panels formed therein, connected at opposite sides to said plates and terminating within the edges of the plate, the distances between the centers of adjacent panels near the floor of the car being less than elsewhere. 75
10. A wall structure for railway cars comprising one or more metallic plates, said wall structure having a plurality of parallel and varying width panels formed therein and connected at opposite sides to the plates and arranged with varying distances between the centers of adjacent panels. 80
11. A wall structure for railway cars comprising one or more metallic plates, said wall structure having a plurality of parallel equal depth and varying width peripherally connected panels formed therein, the distances between the centers of adjacent panels near the floor of the car being less than elsewhere. 85
12. A wall structure for railway cars comprising one or more metallic plates, said wall structure having a plurality of parallel equal depth and varying width peripherally connected panels formed therein, terminating within the edges of the plate, with varying distances between the centers of adjacent panels. 90
13. A wall structure for railway cars comprising one or more metallic plates, said wall structure having a plurality of parallel peripherally connected panels formed therein, the distances between the centers of adjacent panels and the widths of the panels both being smaller near the bottom of the wall than elsewhere. 95

In testimony whereof I affix my signature.

WILLIAM D. THOMPSON.
